CLAIM

The ornamental design for a combined portable load-distributing apparatus and upholstery protector, substantially as shown and described.

DESCRIPTION

FIG. 1 is a perspective view of my new, original and ornamental design for a combined portable load-distributing apparatus and upholstery protector;

FIG. 2 is a top plan view thereof, the bottom plan view being substantially identical thereto;

FIG. 3 is an enlarged front plan view thereof;

FIG. 4 is a rear plan view thereof;

FIG. 5 is a right side plan view thereof; and,

FIG. 6 is a left side plan view thereof.

In FIGS. 1 and 2 the broken lines at three peripheral edges represent stitching which forms part of the claimed design.
